US0D1063542S

(12) **United States Design Patent** (10) **Patent No.:** **US D1,063,542 S**
(45) **Date of Patent:** **** Feb. 25, 2025**

(54) **THERMAL BOTTLE**

(71) Applicant: **WaterH Inc.**, Toronto (CA)

(72) Inventors: **Xia Qu**, Shenzhen (CN); **Xijin Wu**, Shenzhen (CN); **Qi Wang**, Shenzhen (CN)

(73) Assignee: **WaterH Inc.**, Toronto (CA)

(**) Term: **15 Years**

(21) Appl. No.: **29/896,958**

(22) Filed: **Jul. 10, 2023**

(51) LOC (15) Cl. **07-01**

(52) U.S. Cl.

USPC **D7/511**; D7/510

(58) **Field of Classification Search**

USPC ... D7/507, 509–511, 300.1, 300.2, 316, 317, D7/391, 392.1, 322, 318, 396.1, 396.2, D7/629, 900, 500; D3/202; D9/435, D9/530–531

(57) **CLAIM**

The ornamental design for a thermal bottle as shown and described.

DESCRIPTION

FIG. 1 is a top, front, right side perspective view of a thermal bottle, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom, left side perspective view thereof; and,

FIG. 9 is a left side elevation view thereof, showing a handle being rotated downward on a lid.

The dashed broken lines in the drawing depict portions of the thermal bottle that form no part of the claimed design.

1 Claim, 8 Drawing Sheets
